UNITED STATES PATENT OFFICE.

CLOICE B. BAKER, OF ST. LOUIS, MISSOURI, ASSIGNOR OF ONE-HALF TO WILLIAM BAWDEN, OF ST. LOUIS, MISSOURI.

HANDRAIL-COLUMN.

1,345,338.

Specification of Letters Patent.

Patented July 6, 1920.

Application filed April 8, 1920. Serial No. 372,258.

To all whom it may concern:

Be it known that I, CLOICE B. BAKER, a citizen of the United States, residing at St. Louis, state of Missouri, have invented certain new and useful Improvements in Hand-rail-Columns, of which the following is a full, clear, and exact description, reference being had to the accompanying drawings, forming a part hereof.

The present invention is directed to improvements in hand rail columns or brackets, particularly as applied to locomotives. As well understood in the art, a locomotive boiler is usually covered with a lagging of asbestos or mineral wool which is protected by an outer metal sheet or jacket usually made up of sections wrapped around the boiler. The studs to which the hand rail columns are secured pass through the lagging and jacket, the outer ends of the studs being screw-threaded to receive the threaded sockets of the columns, the outer ends of the columns terminating in loops or eyes through which the hand rail is passed. When it becomes necessary for any reason to remove one of the jacket sections, the hand rail must first be withdrawn from the eyes of the supporting columns to permit the unscrewing of the columns from the studs, after which the jacket is pulled out from the studs and removed. Such removal of the jacket is necessitated for example in cases where a leak in the boiler is to be stopped or other repairs made to the boiler shell. The object of my invention is to provide a hand rail column or bracket which does not require the removal of the hand rail when occasion arises to take down a section of the outer jacket. This of course is a decided advantage in that it not only saves time and labor but dispenses with the necessity of making the hand rail in sections which with the ordinary column must be done to facilitate withdrawal of the rail from the supporting loops or eyes of the columns. Under my invention the column is made in two sections which may be separated from one another at any time, one of the sections (the one carrying the loop) being slipped along the rail out of the way while the other section or that coupled to the securing stud can be readily unscrewed from the stud without disturbing the rail. The advantages of the invention will be more fully apparent from the following de-

tailed description in connection with the accompanying drawings in which—

Figure 1 represents a side elevation of a locomotive showing my invention applied thereto; Fig. 2 is an enlarged cross-section through the boiler shell, the lagging, and outer jacket thereof, showing my improved column in elevation, applied thereto; Fig. 3 is a detached elevational view of the improved column; Fig. 4 is a longitudinal middle section therethrough; and Fig. 5 is a perspective of a column parted so as to permit the shifting of the outer section along the hand rail.

Referring to the drawings, 1 represents the shell of the boiler, 2, the lagging, and 3 the outer jacket, the studs 4 leading from the shell or boiler wall through the lagging and jacket and terminating at their outer ends in a threaded portion to which the columns 75 or brackets are secured as well understood in the art.

In the present embodiment of my invention the hand rail column is composed of two sections or members, the inner or bottom section comprising an intermediate cylindrical portion 5 terminating at one end in an expanded base 5', and at the opposite end in a slightly enlarged threaded portion 5", the bottom of the member being provided with the usual threaded socket *a* for receiving the threaded terminal of the stud 4. The outer member or section of the column comprises an outer terminal loop or eye 6 for the reception of the hand rail 7 as usual in the art, and an inner reduced threaded portion or extension 6' of the same cross-section as the threaded portion 5" of the first section, the ends of the portions being brought into abutting relation when the same are assembled. The reduced threaded extension 6' is offset from the loop 6 by an inclined outwardly flaring shoulder *s*, said shoulder receiving the correspondingly beveled end of a coupling sleeve 8 screwed over the threaded portions 5", 6', the length of the sleeve corresponding to the combined lengths of the threaded portions over which the same is passed. The length of the intermediate portion 5 of the inner column section is sufficient to allow the sleeve 8 to be wholly unscrewed from the threaded portion 6' of the outer section so that when occasion requires, said outer section may be readily detached from the bottom 110

section (Fig. 5; also dotted lines Fig. 4). In practice, when occasion arises to remove a section of the jacket 3, the operator simply unscrews the coupling sleeve 8 sufficiently to separate the two sections of the column, the outer section being then moved along the rail 7 out of the way of the bottom section to be removed (Fig. 5). With the outer column section out of the way, the bottom section of the column is then unscrewed from the stud 4, permitting the jacket to be passed off the stud and thereby removed from the boiler without disturbing the hand rail. In the same manner the lagging may be passed off the stud 4 should the operator or repair man desire to get at the shell of the boiler for any purpose such as repairing a leak at the base of the stud. After the leak has been repaired the lagging and jacket are restored to the stud, the bottom column section is screwed to the stud and the outer section is slipped along the rail back to original position against the inner section, and the sleeve 8 screwed home against the shoulder 8, and this without the necessity of disturbing the hand rail. The column is therefore a time saver and reduces the cost of repairs. It is of course apparent that I may change the construction in minor details without departing from the nature or spirit of the invention. The advantage of the present construction lies in the fact that when the coupling sleeve which spans the joint formed by the abutting terminals between the column sections is moved past the point or unscrewed sufficiently to release the outer section, the latter can be moved to one side or in a direction at right angles to the axis of the column. The outer section being thus moved to one side, allows the bottom section to be removed independently from the securing stud 4 without disturbing the hand rail.

Having described my invention what I claim is,

1. A hand rail column comprising an outer section to which the rail is applied, and an inner section to be attached to a fixed support, and separable from the first section, and means disposed about the peripheries of the sections for coupling the sections together.

2. A hand rail column comprising an outer section to which the rail is applied, an inner section, means on the bottom of said inner section for securing the same to a fixed support, and means engaging the peripheral walls of the sections for coupling the sections together.

3. A hand rail column comprising an outer section to which the rail is applied, an inner section, means on said inner sec-

tion for securing the same to a fixed support, and a movable member encompassing adjacent portions of the sections for coupling the sections.

4. A hand rail column comprising an outer section provided with a hand rail-receiving loop and a reduced threaded extension leading and offset therefrom, a bottom section terminating at one end in a threaded portion of the same cross-sectional diameter with the reduced threaded extension of the outer section and adapted to be placed in abutting relation therewith, the bottom section having a slightly reduced portion leading from the inner end of the threaded portion thereof, a coupling sleeve passed over the threaded portions of the abutting sections, the length of the reduced portion of the bottom section being sufficient to allow of a complete unscrewing of the sleeve from the threaded extension of the outer section to permit of separation of the sections.

5. A hand rail column comprising two sections having adjacent ends in abutting relation, and a peripheral coupling member spanning the joint between the sections.

6. A hand rail column comprising two sections in abutting relation disposed about a common axis, a coupling sleeve spanning the joint between the sections and adapted to be moved past the joint aforesaid to allow one of the sections to be moved in a direction at right angles to the axis aforesaid.

7. A hand rail column comprising a bottom section having at one end an expanded base, a central reduced portion, and a slightly enlarged threaded portion at the opposite end, and an outer section composed of a hand rail-receiving loop and of a reduced threaded extension leading and offset from the looped portion by an inclined outwardly flaring shoulder, the threaded portions of the sections being of the same cross-sectional diameter and forming a butt joint with one another, a screw sleeve passed over the threaded portions and spanning the joint aforesaid for coupling the sections together, one end of the sleeve being beveled to engage the inclined shoulder aforesaid, the length of the intermediate reduced portion of the bottom section being such as to allow the sleeve to be fully unscrewed from the threaded extension of the outer section, thereby permitting said section to be moved to one side along the rail to permit removal of the bottom section.

In testimony whereof I affix my signature, in presence of two witnesses.

CLOICE B. BAKER.
